UNITED STATES PATENT OFFICE

2,655,617

ELECTRIC SPARK IGNITION APPARATUS

John Andrew Laird, Coventry, England, assignor
to Joseph Lucas Limited, Birmingham, Eng-
land

Application July 16, 1951, Serial No. 236,966
In Great Britain July 20, 1950

7 Claims. (Cl. 315—180)

1

This invention relates to electric spark ignition apparatus of the kind which includes a condenser for effecting a relatively large discharge across an ignition gap in an internal combustion prime mover, and particularly an ignition gap of the so-called low voltage type in which a semi-conductive path is provided between the gap electrodes. The object of the invention is to provide an effective and reliable apparatus in a simple form.

The invention comprises the combination of charging means, a resistance in series with the charging means, and a control gap in parallel with the resistance, the latter being adapted for connection to an ignition gap, the necessary capacity being provided by either the self-capacity of the charging means and/or the associated conductors, or by a separate condenser connected in parallel with the charging means.

In the accompanying diagrams:

Figures 1 and 2 illustrate two embodiments of the invention.

Referring to Figure 1, there is provided an induction coil comprising primary and secondary windings *a*, *b*, the primary winding being energised from a battery or other direct current source through a rotary interrupter *c*, across which latter may be connected the usual spark-suppressing condenser *d*. In parallel with the secondary winding *b* of the coil may be connected the condenser *e* to be charged by the coil. Where the self or distributed capacity of the coil and/or the conductors connected thereto is adequate the condenser *e* need not be provided, or alternatively the required capacity may be provided in part by the self or distributed capacity and an additional condenser. If desired the coil may be connected to the condenser through a rectifier as indicated by *f* in Figure 2. In series with one end of the secondary winding *b* and at a position beyond the condenser is connected a resistance *g* of any appropriate value, for example, 0.5 megohm. Also in parallel with the resistance (and rectifier when used) is provided a circuit containing the control gap *h*. The resistance *g* may be connected directly to the ignition gap *i*, but preferably a gap *j* is provided between the resistance and the ignition gap. It is also advantageous to insert an inductance (as *k* Figure 2) in any convenient position to control the rate of discharge of the condenser.

The arrangement is such that the first effect of an impulse from the induction coil is to break down the ignition gap *i*, or both the ignition gap and the series gap *j* (when the latter is provided).

2

Later when the potential difference across the ends of the resistance *g* rises to a sufficient amount the control gap *h* breaks down and allows the charge stored in the condenser by the previous impulse to discharge across this gap. After the discharge across the ignition gap has ceased, the residual energy of the coil serves to re-charge the condenser.

Figure 2 illustrates the application of the invention to a system which includes a plurality of ignition gaps, as in a 4-cylinder engine, where each gap in turn is connected to the system through a distributor comprising a rotary arm *m*, and an arrangement of stationary electrodes *n*, 15 the gap *j* above mentioned being provided between the arm and each of the adjacent electrodes *n* in turn. Where a wipe-distributor is used, in which the rotary arm wipes across the successive electrodes, a gap as *j* may be provided 20 in series with the distributor.

As an alternative to the above described induction coil, any other suitable charging means may be used, such as a magneto, an alternating current source, or an electrostatic machine.

Having thus described my invention what I claim as new and desire to secure by Letters Patent is:

1. Electric spark ignition apparatus comprising, in combination, charging means having a circuit connected to an ignition gap adapted to break down upon the initial charging impulse of said means, a resistance in series with said circuit, capacity included in the circuit adapted to store energy therein, and a control gap connected in parallel with said resistance and adapted to break down at a higher potential than the breakdown potential of the ignition gap when the potential across the resistance rises to an appropriate value due to flow of current in the circuit following the initial breakdown of the ignition gap, whereby the stored energy in the circuit is released and results in a relatively large discharge across the ignition gap.

2. Apparatus according to claim 1, comprising an additional gap in the circuit in series with said resistance and control gap, and adapted to break down upon the initial charging impulse.

3. Apparatus according to claim 1, comprising a distributor in said circuit for a plurality of ignition gaps in a multi-cylinder engine, the said distributor being formed to afford an additional gap in series with the circuit of each ignition gap, said additional gaps being adapted to 50 break down upon the initial charging impulse.

4. Apparatus according to claim 1, comprising a condenser connected in parallel with the charging means.

5. Apparatus according to claim 1, comprising a condenser connected in parallel with the charging means through a rectifier.

6. Apparatus according to claim 1, comprising an inductance connected in the said circuit for controlling the rate of discharge.

7. Apparatus according to claim 1, comprising 10 an ignition gap of the low-voltage type in which

a semi-conductive path is provided between the gap electrodes.

JOHN ANDREW LAIRD.
